ABSTRACT OF THE DISCLOSURE

Prostaglandins and/or prostaglandin-like compounds are synthesized by a microbiological process using *Pseudomonas aeruginosa* in a nitrogen-containing, fatty acid-free culture medium.

This invention relates to a class of biologically active lipids and more particularly to a process for the biosynthesis of a class of lipids referred to as prostaglandins.

In recent years a group of unsaturated carboxylic acids containing 20 carbon atoms, in which C-8 to C-12 compose a five-membered ring, have been identified as existing in biological systems. These compounds have been given the common generic name "prostaglandins" and they have been the subject of intensive research with respect to their various roles in biological systems, their use as pharmacologically active agents in treating certain conditions, and their use as precursors in the formation of new drugs.

Although there are a number of prostaglandins known, the process for their production which is the subject of this invention is concerned with so-called prostaglandins (A, E and F series), each of which has characteristic substituents on the carbon chains which vary according to their fatty acid precursors, and with prostaglandin-like materials.

Thus the prostaglandins designated A have a characterizing ket grouping on C-9 and three possible structures for prostaglandin A (PGA) may be represented as

depending upon whether the fatty acid precursor is 8,11,14-eicosatrienoic acid, 5,8,11,14-eicosatetraenoic acid or 5,8,11,14,17-eicosapentaenoic acid. In similar fashion, prostaglandins designated E have a characterizing keto grouping on the C-9 and a hydroxyl grouping on the

2

C-11 and may be represented by the following structural formulas

Prostaglandins designated F_a have characterizing hydroxyl groupings on the C-9 and C-11 and may be represented as having the following structural formulas:

The prostaglandins may be isolated from biological materials, and a 16-step synthesis leading to PGF_{2α} has been reported (see "Total Synthesis of Prostaglandins" by Elias J. Corey, *Proc. Robert A. Welch Found. Conf. Chem. Res.* (Pub. 1969) 12, 51-79). The conversion of prostaglandins derived from the coral *Plexaura homomalla* to PGF_{2α} has been reported (see "Novel Prostaglandin Synthesis" by G. L. Bundy, F. Lincoln, N. Nelson, J. Pike and W. Schneider, *Ann. N.Y. Acad. Sci.* 1971, 180, 76-90). Work has also been done on the conversion of novel unsaturated fatty acids to biologically active Δ^2 -prostaglandins (see "Recent Developments in the Biosynthesis and Analyses of Prostaglandins" by D. A. Van Dorp, *Ann. N.Y. Acad. Sci.* 1971, 180, 181-199).

U.S. Pat. 3,290,226 describes a process for the biosynthesis of prostaglandins in which unsaturated fatty acids,

having a 1,4-diene group in their chains, are subjected to the oxygenating activity of a species of Subphylum 2 of Phylum III. U.S. Pat. 3,644,502 discloses a process for chemically synthesizing prostaglandins from o-methoxyphenylacetic acid.

There is, however, a need for an improved process for producing the prostaglandins and prostaglandin-like materials. Such an improved process should desirably be less complicated and time-consuming than those now employed and should make it possible to provide such materials at lower cost.

Since prostaglandins occur endogenously in animals including humans, they find one very important use in studying the inhibitions of these naturally-occurring materials by such antagonists as polyphloretin phosphate, dibenzoxazepine hydrazine derivatives, the active ingredients in aspirin, etc. In general, these compounds are known to have hypotensive and smooth muscle-stimulating activity. Prostaglandins have been used in performing therapeutic abortions in several countries, and their use has been endorsed by the Committee on the Safety of Drugs in Great Britain. They have also been found to have a bronchodilating effect in the treatment of asthmatics and they are known to have a regulating effect on blood pressure and sodium excretion. (See for example *Science* Volume 171, pp. 502-504 (1971).)

It is therefore a primary object of this invention to provide an improved process for producing prostaglandins and prostaglandin-like substances. It is another object of this invention to provide a process of the character described which is relatively simple to manipulate and which may make it possible to produce prostaglandins and prostaglandin-like substances economically. Other objects of the invention will in part be obvious and will in part be apparent hereinafter.

According to the process of this invention, prostaglandins and prostaglandin-like substances are synthesized by strains of the bacterium *Pseudomonas aeruginosa* grown in nitrogen- and carbon-containing culture media in the presence of oxygen.

The culture medium must be one which provides nitrogen and carbon in usable forms. Exemplary of such media are a broth containing a hydrolyzed or partially hydrolyzed protein such as soya protein as the nitrogen source and dextrose as the carbon source and a chemically defined broth containing many of amino acids known to form proteins serving as both the nitrogen and carbon sources. The culture medium may be enriched with heat-inactivated human serum, rabbit serum albumin, etc., serving as additional protein sources. The amount of such protein additive or additives should preferably be no greater than about 4% by weight of the growth medium.

The temperature of the culture during the production of the prostaglandins and prostaglandin-like substances may range between about 4° C. and 40° C., the higher temperatures being preferred inasmuch as the production rate is materially increased with increasing temperature.

The pH of the culture medium just prior to inoculation with *Pseudomonas aeruginosa* should be about neutral, and the formation of the prostaglandin product may take place within a pH range of from about 5 to 9.

The prostaglandin product is extracted from the culture medium with ethyl acetate or other appropriate solvents and it is identified by radioimmunoassay techniques.

The following examples, which are meant to be illustrative and not limiting, are provided to further describe the process of this invention.

Pseudomonas aeruginosa was inoculated into 1.6 ml. trypticase soy broth (TSB), free of any added fatty acids, and the cultures incubated at 37° C., 23° C. and 4° C. Samples of 0.3 ml. were taken at various time intervals, diluted with saline, centrifuged and the supernatant fluids measured for F prostaglandin content. In this example, as well as in all of the following examples, the prostaglandins

were identified through the use of the radioimmunoassay technique of Stylos et al. (see *Intra-Science Chem. Rept.*, Volume 6, Number 1 (1972) pp. 67-71) with the following modifications. To increase sensitivity of the assay 0.1 ml. of $^3\text{H}-\text{F}_{1\alpha}$ containing approximately 7500 d.p.m. (~ 10 pg.) was used instead of $^3\text{HF}_{2\alpha}$. Bound prostaglandins were separated from unbound by centrifugation of 2nd antibody precipitates. The supernatants were decanted and the tubes were inverted onto paper towels to drain 10 minutes and any remaining fluid removed by suction. The precipitates were dissolved in 0.2 ml. of 0.1 N NaOH and decanted into vials containing 7 ml. of scintillation fluid. The tubes were rinsed twice with 1.5 ml. of fluid and these rinses added to the scintillation vials for counting. The PGF immunoassay according to this modified technique has been twice validated in double blind experiments with GLC/mass spectrometry data. The prostaglandins (or prostaglandin-like) compounds were also identified by thin layer partition chromatography.

The production of prostaglandin and prostaglandin-like substances using a series of such cultures is given below in Table 1.

TABLE 1
Prostaglandin production by *Ps. aeruginosa* using trypticase soy broth

	Temperature, ° C.:	Growth time		Production (ng./ml.)
		Days	Weeks	
30	37	0		0.00
	37	1		0.00
	37	2		0.60
	37	3		0.81
	37	6		1.20
	23	0		0.00
	23	1		2.52
35	23	2		2.80
	23	4		2.52
	4	0		0.00
	4	2		0.45
	4	4		0.00

40 To determine the oxygen requirement for synthesis of the prostaglandin product, cultures were incubated in glass tubes with cotton plugs to allow free air exchange and in screw cap vials to obtain microaerophilic conditions. *Pseudomonas aeruginosa* was inoculated into 1.8 ml. TSB or 1.8 ml. TSB containing 1 $\mu\text{g}./\text{ml}$. arachidonic acid and all cultures incubated at 37° C. Samples of 0.3 ml. were removed at various time intervals, and treated as described for the above examples. The quantities of prostaglandin product resulting under these conditions are given in 50 Table 2.

TABLE 2
Prostaglandin production under varying aerobic conditions
[In ng./ml.]

55 Aerobic conditions	0 day	1 day	2 days	Remarks
With air	0.00	0.85	1.41	Heavy growth of organism.
With air plus arachidonic acid	0.00	0.75	0.95	Do.
Microaerophilic	0.00	0.00	0.00	Do.

60 The need for oxygen is clearly shown in Table 2. This table also illustrates the effects of the addition of arachidonic acid which in mammalian tissues is the fatty acid precursor of PGE₂ and PGF_{2 α} . In general it may be seen that although heavy growth of the microorganism occurred when the arachidonic acid was added, the microorganism was unable to cyclize (effect the conversion of) the arachidonate under the conditions described.

70 A number of other bacterial strains were used in place of *Pseudomonas aeruginosa* to determine whether they would produce a prostaglandin product under the same conditions used to obtain the data in Table 2. The bacteria used were *Salmonella enteritidis*, *Salmonella typhimurium* (2 strains), *Escherichia coli*, *Salmonella St. Paul*, *Salmon-*

ella typhosa, a group D *Salmonella* and a *Staphylococcus*. None of these produced a prostaglandin or prostaglandin-like substance in either TSB or in TSB supplemented with arachidonic acid or with human serum.

The trypicase soy broth was enriched with varying amounts of heat-inactivated human serum to determine the effect of serum components on prostaglandin biosynthesis. Tubes containing 1.7 ml. of enriched broth were incubated at 37° C. and 0.3 ml. samples were removed after 1, 3 and 5 days. Samples were diluted with 0.9 ml. saline and treated as described above. The quantities of prostaglandin production are given in Table 3.

TABLE 3
Prostaglandin production in TSB and serum
[In ng./ml.]

Percent by weight		Days at 37° C.			
TSB	Serum	0 day	1 day	3 days	5 days
	100	0.00	0.34	1.53	-----
50	50	0.00	1.17	2.21	4.95
70	30	0.00	1.23	2.40	2.40
90	10	0.00	1.37	1.43	2.40
*100	0	0.00	0.00	0.81	1.40

*Figures for 100% TSB taken from an earlier example for comparison.

The inclusion of up to about 50% by weight of the heat-inactivated human serum generally increased the production of the prostaglandin product in the longer reaction runs.

For more rigorous identification of the prostaglandins and prostaglandin-like substances produced by the process of this invention, *Pseudomonas aeruginosa* culture supernatants were extracted by ethyl acetate and separated by thin layer chromatography. A flask containing 100 ml. TSB was inoculated and incubated for 4 days at 37° C. (the pH changed from 7.3 to 8.65 during this time). The supernatant was brought to pH 4.0 with HCl and extracted with 200 ml. ethyl acetate. The aqueous phase was removed and the ethyl acetate phase washed twice with 10% distilled water and dried over sodium sulfate. The clarified ethyl acetate phase was taken to dryness under N₂, solubilized and chromatographed using a solvent system which separated the A, E and F prostaglandin species: ethyl acetate-acetone-acetic acid (95:5:1). Zones migrating with tritiated standards of A, E and F prostaglandins were eluted and measured in the radioimmunoassay. The amount of prostaglandins found in the three PG zone eluates were as follows: PGF, 8.7 ng.; PGE, 3.1 ng.; PGA, 16.2 ng. Thus the process of this invention is capable of producing prostaglandins and prostaglandin-like substances of the A, E and F series.

A chemically-defined broth, designated Bacto-Synthetic Broth AOAS by its supplier Difco Co., and prepared according to the formula given in *J. AOCA*, 47: 176 (1964), was substituted for the trypicase soy broth used in the previous examples. This synthetic culture medium contained some eighteen amino acids; but it did not contain any fatty acids, which, if present, could be considered as precursors for prostaglandins or prostaglandin-like materials.

Pseudomonas aeruginosa was grown in the chemically-defined medium under a number of different conditions as summarized below in Table 4. The resulting culture supernatants were separated by centrifugation and measured for prostaglandin content by radioimmunoassay. The amounts of prostaglandins formed are given in Table 4.

TABLE 4
Prostaglandin production by *Ps. aeruginosa* using chemically-defined culture medium

Days	° C.	Additive	Production (ng./ml.) ¹			Final pH ²
			PGF	PGE	PGA	
3	37	None	0.4	0.5	3.3	8.2
3	37	2X phosphate buffer.	0.3	0.4	2.7	7.8
3	37	5X amino acetic acid.	0.3	0.4	3.0	8.3
10	37	3X glucose	0.4	0.4	3.7	7.9
1	37	None ³	1.0	-----	17.5	7.9
2	28	3X glucose	1.0	-----	17.5	7.9
9	4	None ³	1.0	-----	17.5	7.9
1	37	do ³	1.6	-----	26.8	8.2
10	28	do ³	1.6	-----	26.8	8.2

¹ All values corrected for medium background.

² Initial pH of chemically-defined medium was 7.1.

³ Single run using decreasing temperatures.

From these results it will be seen that additional amino acetic acid (glycine), glucose or phosphate buffer did not appreciably alter the yields. The principal prostaglandin biosynthesized was PGA, while lesser amounts of PGE and PGF were formed.

It is evident from these examples that the process of this invention provides a simple synthetic route for the production of prostaglandins and prostaglandin-like materials; and it offers the possibility for large-scale economic synthesis of these materials.

It will thus be seen that the objects set forth above, among those made apparent from the preceding description are efficiently attained and, since certain changes may be made in carrying out the above process without departing from the scope of the invention, it is intended that all matter contained in the above description shall be interpreted as illustrative and not in a limiting sense.

We claim:

1. A process for the biosynthesis of prostaglandins, comprising the steps of
  - (a) growing the bacterium *Pseudomonas aeruginosa* in the presence of oxygen in a culture medium essentially free of fatty acids and containing available nitrogen and carbon therby to form prostaglandins; and
  - (b) isolating the product prostaglandins thus formed.
2. A process in accordance with claim 1 wherein said culture medium is trypicase soy broth and said nitrogen is present in the form of protein naturally present in said soy broth.
3. A process in accordance with claim 2 wherein said trypicase soy broth contains an additional source of protein.
4. A process in accordance with claim 2 wherein said additional source of protein is heat-inactivated human serum.
5. A process in accordance with claim 1 wherein said culture medium is a chemically-defined medium containing amino acids which serve as said source of nitrogen.
6. A process in accordance with claim 1 wherein said available carbon is provided in the form of dextrose.
7. A process in accordance with claim 1 wherein said growing step is carried out between about 4° C. and 40° C.
8. A process in accordance with claim 1 wherein the growing of said bacterium is carried out at a pH between about 5 and 9.
